No. 748,910.

PATENTED JAN. 5, 1904.

F. ACKER.
COFFEE URN.

APPLICATION FILED NOV. 19, 1902.

NO MODEL.

UNITED STATES PATENT OFFICE.

FINLEY ACKER, OF PHILADELPHIA, PENNSYLVANIA.

COFFEE-URN.

SPECIFICATION forming part of Letters Patent No. 748,910, dated January 5, 1904.

Application filed November 19, 1902. Serial No. 131,940. (No model.)

To all whom it may concern:

Be it known that I, FINLEY ACKER, a citizen of the United States, residing in the city and county of Philadelphia, State of Pennsylvania, have invented new and useful Improvements in Coffee-Urns, of which the following is a specification.

My invention consists of a coffee-urn which is composed of an urn proper, a vessel for receiving ground coffee, the same having a percolator and water-spraying device therein, a chamber for measuring the amount of water desired to be converted into fluid coffee, and a tank for primarily boiling the water from which the coffee is to be made, the parts being hereinafter described and the novel features of the same being pointed out in the claims.

Figure 1 represents a vertical section of a coffee-urn embodying my invention. Fig. 2 represents a side view of a detached portion thereof. Fig. 3 represents a horizontal section on line $x-x$, Fig. 2. Figs. 4 and 5 represent top views of detached portions in different positions.

Similar letters of reference indicate corresponding parts in the figures.

Referring to the drawings, A designates a tank, the same being adapted for primarily receiving water, and is provided with a coil A', of steam-pipe, or an electrical or other device whereby the water in said tank may be boiled. Connected with said tank is a vessel B, which is in communication with said tank A by means of the valved pipe C, said vessel having a heating or boiling device B' and a gage D for indicating the height of water in said vessel, said vessel serving to measure the water for the quantity of fluid coffee it is designed to make, it being also provided with a vent E, the same being open to the atmosphere for evident purposes.

F designates what I term a "coffee-maker" and which consists of a cylindrical or other shaped receiver G in communication with the chamber B by means of the pipe H. At the base of said receiver is the valved pipe J, which is connected with the urn K. Within the receiver, at the lower portion thereof, is the strainer and filter-plate L, above which is a foraminous dome-shaped or convex diaphragm N, which depends from the tube M,

the upper portion of which is open, forming the vent P. Fitted on said tube above the diaphragm N is the flanged tray Q, the bottom of which is perforated or foraminous, said plate being adapted to be held at various heights in regard to the amount of ground coffee to be used by means of the ring R and screw or pin R', which latter may be placed in either of the openings S in the side of the tube M one above the other.

Depending from the bottom of the vessel B is the collar T, in the side of which is the angular slot U, which is adapted to receive the pin V as a bayonet-joint, said pin projecting outwardly from the sleeve W, which enters the collar T, and has a flange X on its upper end, the same normally resting on the bottom of said collar, thus limiting the descent of said sleeve and properly holding the same in position, it being noticed that said sleeve forms a downward continuity of the pipe H and its lower end freely enters an opening in the lid G' of the member F, so that water flowing from the vessel B through the pipe H passes through the sleeve W and the opening in the lid G', and so enters the receiver G. The pipe J at the bottom of the receiver G freely enters an opening in the lid K' of the urn K, it being noticed that the coffee-maker F rests on said lid K'. Now when it is desired to displace the coffee-maker, either for receiving the coffee-grounds or replenishing the same with ground coffee or for other purposes, the sleeve W is raised, whereby it withdraws from the lid G' and is elevated above the same. The pin V ascends in the vertical member of the slot U, and when it reaches the horizontal member thereof it is turned thereinto, whereby the sleeve is sustained in its elevated position. The coffee-maker may now be raised, the pipe J at the bottom thereof emerging from the opening in the lid K', thus disconnecting the coffee-maker from the urn and removing it therefrom.

Y designates the vent-pipe of the urn K, the same opening into the interior thereof and having an outwardly-extending branch Y', so that air can enter the urn to permit the discharge of the fluid coffee when the cock Y² is opened, it being noticed that the head Y³ of said cock has a segment Z on the rear portion of its periphery, the same being

adjacent to the open end of the branch Y', so that when the cock is closed the said segment abuts against said end of the branch and closes the same, and consequently the 5 vent-pipe, thus preventing the escape of the aroma of the coffee in the urn. When, however, the cock is opened, the said segment of the head moves from the end of the vent-pipe and uncovers said end, whereby air may 10 enter the vent and supply the interior of the urn for purposes hereinbefore stated. (See Figs. 4 and 5.)

The operation is as follows: The sleeve is raised, as hereinbefore stated, and the coffee- 15 maker is disengaged from the urn. The lid G' is removed and the tray Q withdrawn. The proper quantity of ground coffee is now placed in said vessel and rested on the dia- phragm N, after which the tray is returned 20 to its adjusted position, the cover of the vessel reapplied, and the coffee-maker restored upon the urn. The sleeve W is now lowered and inserted in the lid G', as in Fig. 1. It will now be noticed that the amount of water 25 supplied from the tank A to the measuring-chamber B may be adjusted by means of the valve in the pipe C. The boiling water then flows through the pipe H and sleeve W into the vessel G and passes through the ground 30 coffee on the diaphragm N, thus making an infusion of the coffee. The valve J is opened after the coffee has sufficiently infused and the beverage percolates and filters through the plate L, and so enters the urn K. It will 35 be noticed that the water entering the vessel G passes through the tray Q in numerous streams or sprays, owing to the openings in the bottom of said plate, and so is thoroughly distributed over and upon the ground coffee. 40 In some cases it may be desirable to supply the vessel G with only a small quantity of water in order to saturate the ground coffee and then to admit a larger supply of water, which is sprayed upon the ground coffee and 45 caused to directly circulate through the dia- phragm N and the strainer and filter below the same.

The tank A, the chamber B, the vessel G, and urn K are suitably jacketed and may be 50 insulated or packed in order to retain the heat within said parts. The tank A and vessel B will be supported in any suitable manner.

Various changes may be made in the de- 55 tails of construction without departing from the general spirit of my invention, and I do not, therefore, desire to be limited in each case to the same.

Having thus described my invention, what I claim as new, and desire to secure by Letters 60 Patent, is—

1. In a coffee-making device, a primary

heating-tank, a water-measuring tank and a coffee-making vessel detachably connected with said measuring-tank.

2. In a coffee-making device, an urn, a 65 coffee-making vessel mounted on said urn, a water-tank on said vessel, detachable liquid-conveying connections between said urn and said vessel and between said vessel and said tank and valves controlling the flow of liquid 70 through both said connections.

3. In a coffee-urn, a receptacle for ground coffee, an urn proper for fluid, and a communicating valved pipe for said parts, said pipe freely entering the lid of said urn proper. 75

4. In a coffee-urn, a water-receiving ves- 80 sel, a receptacle for ground coffee, an urn proper for fluid coffee, a communicating pipe for said vessel and receptacle, a communicat- ing pipe for said receptacle and urn proper, 85 said pipes being respectively formed of de- attachable parts and valves in said communi- cating pipes.

5. In a coffee-urn, a coffee-urn proper, an air-vent therefor and a discharge cock or 85 valve for said urn proper, said cock or valve being adapted to close and open said vent.

6. In a coffee-urn, a coffee-urn proper, an air-vent therefor, and a discharge cock or 90 valve, the inlet end of said vent being adja- cent to the head of said cock or valve, said head having a segmental surface adapted to engage with said end to close said vent and to be removed therefrom to open the same.

7. In a coffee-urn, a removable coffee-mak- 95 ing vessel having a lid thereon and a vertical opening in said lid, a stationary tank above the same, a collar depending from said tank and communicating therewith and a verti- cally-movable sleeve partly occupying said 100 collar and having its lower end adapted to enter the opening in said lid and means on said collar and sleeve for holding said sleeve elevated outside of said opening and clear of said lid. 105

8. In a coffee-urn, a removable coffee-mak- 110 ing vessel having a lid thereon and a vertical opening in said lid, a stationary tank above the same, a collar depending from said tank and communicating therewith, a vertically- 115 movable sleeve partly occupying said collar and having its lower end adapted to enter the opening in said lid, means on said collar and sleeve for holding said sleeve elevated outside of said opening and clear of said lid and a valve intermediate of said tank and collar.

FINLEY ACKER.
